UNITED STATES PATENT OFFICE.

HARVEY LEWIS, OF CHICAGO, ILLINOIS.

DESIGN FOR A BREAD RECEPTACLE OR SERVER.

50,996.

Specification for Design.

Patented July 3, 1917.

Application filed March 17, 1917. Serial No. 155,625. Term of patent 7 years.

To all whom it may concern:

Be it known that I, HARVEY LEWIS, a citizen of the United States, residing in Chicago, county of Cook, and State of Illinois, have invented a new, original, and ornamental Design for a Bread Receptacle or Server, of which the following is a specification, reference being had to the accompanying drawing, forming part thereof.

The figure is a perspective view of the jar constituting my bread receptacle or server, and showing my new design.

I claim:

The ornamental design for a bread receptacle or server, as shown.

HARVEY LEWIS.

Witnesses:

LEO STERN,

LEO SARON.
